INCINERATOR SPARK ARRESTER

Peter Grover Beveridge, Bremerton, Wash.

Application August 1, 1935, Serial No. 34,245

4 Claims. (Cl. 261—118)

(Granted under the act of March 3, 1883, as
amended April 30, 1928; 370 O. G. 757)

This invention relates to a spark arrester especially intended for use in incinerators.

Although this invention is capable of general use wherever it is necessary or desirable to eliminate sparks, and incidentally solid particles of smoke or solid particles of the products of combustion, this invention is intended for use on shipboard and more particularly for use on military and naval vessels.

10 In military and naval vessels it is a military disadvantage to allow any uncontrolled smoke or particles to escape therefrom as such would tend to reveal the location of the vessel. It is likewise a military disadvantage to dispose of 15 garbage by throwing it from aboard; nevertheless, the garbage must be disposed of for sanitary reasons, and with this invention it becomes possible to safely use an incinerator for disposing of garbage or other refuse and at the same time avoid the escape of any visible smoke or sparks.

20 Although spark arresters and smoke consumers were well known prior to the present invention, yet the prior devices were unsuitable for use on military and naval vessels either because of being 25 incapable of being accommodated in the limited space available on board such vessels or because they were too short-lived to operate satisfactorily.

This invention is placed between the incinerator and the smoke uptake or stack and removes 30 the sparks or visible solid particles from the incinerators as the smoke passes from the incinerator to the uptake.

With the above and other objects in view, the invention consists in the construction, combination 35 and arrangement of parts as will be herein-after more fully described.

Fig. 1 is a side elevational view, partly in section, of this invention; and,

Fig. 2 is an end view looking from the left of 40 Fig. 1, the incinerator having been omitted.

There is shown at 10 a spark arrester which is in the form of a metal box suitably shaped and lined with fire brick 11. The fire brick 11 is so placed as to form a smoke passage 12 extending through the opposite sides of the box from a flanged entrance 13 at one end which is adapted to be secured to flange 14 of the incinerator 15 to a flanged exit 16 at the other end adapted to be secured to a flange 17 of a smoke

50 stack or uptake 18. Extending through the box 10 from the rear 19 to the front 20 and above the smoke passage 12 is a water pipe 21 provided with a plurality of spray holes 22, the holes 22 being set at an angle of approximately 15° from the bottom so that water from any suitable

source may be sprayed into a curtain of water 23 at an angle of 15° to the vertical across the smoke passage 12. The smoke and sparks from the incinerator 15 passing through the passage 12 will be completely exposed to this water curtain 23 and the water curtain will thereby wash the smoke of all sparks or solid particles which will then be collected in a water trap 24 formed at the bottom of the box 10. This water trap 24 is provided with a water seal consisting of a baffle 25 so that none of the smoke or fumes can escape thereunder.

The water trap 24 is connected with an extension 26 at the front thereof communicating under the baffle 25 to the water drain pipe 27 as an 15 outlet 28 maintaining the depth of the water in the trap 24 at just above the lower edge of the baffle 25, thereby permitting the seal to be maintained. This extension 26 is provided with a open by the latch 31 when desired, permitting 20 open by the latch 31 when desired, permitting the solid particles in the trap 24 to be removed therefrom periodically when necessary.

A water gage 32, provided on the side of the extension 26 allows the level of the water in the trap 24 to be inspected without opening the cover. The rear wall 19 is provided with an eye-piece 33 hinged thereto as at 34, permitting the smoke passage 12 to be inspected whenever desired. A manhole cover 35 is likewise provided in the rear wall 19, permitting an entrance to the box 10 whenever necessary.

In operation the smoke from the incinerator passing in the direction of the arrester, through the smoke passage 12, is exposed to the water curtain 33, washing out all solid particles and live sparks. Solid particles and live sparks are caught in the trap 24 and the current of water flowing from the trap carries the particles out under the baffle seal 25 collecting them in the extension 26 so that they may be removed therefrom periodically, when necessary, through the opening provided by the cover 29.

The invention described herein may be manufactured and used by or for the Government of 45 the United States of America for governmental purposes without the payment of any royalties thereon or therefor.

I claim:

1. A spark arrester comprising a metallic box, a 50 fire brick lining in said box providing a smoke passage therethrough, a water spray pipe extending across but above said smoke passage through said box and a water trap formed at the bottom of said box, an extension at one side 55

of said box, a baffle in said box dividing said extension from said water trap and providing a water seal preventing escape of any gases thereunder but permitting the water to flow from the trap to said extension.

2. A spark arrester comprising a metallic box, a fire brick lining in said box providing a smoke passage therethrough, a water spray pipe extending across but above said smoke passage through said box and a water trap formed at the bottom of said box, an extension at one side of said box, a baffle in said box dividing said extension from said water trap and providing a water seal preventing escape of any gases thereunder but permitting the water to flow from the trap to said extension, means in said extension maintaining the depth of water in said extension and said water trap, and means on said extension permitting periodical cleaning out of the water trap.

3. A device of the character described for eliminating visible particles from smoke, com-

prising a chamber having a horizontal smoke passageway extending therethrough, fire brick lining said passageway and forming a recess in the top portion thereof, and a conduit in said recess and placed completely above the path of the smoke through said passageway, said conduit having holes therein for creating a water curtain across said passageway.

4. A device of the character described for eliminating visible particles from smoke, comprising a chamber, said chamber having a horizontal smoke passageway extending therethrough and having formed in the bottom thereof a water trap, fire brick lining said passageway and forming a recess in the top portion thereof, and a conduit in said recess and placed completely above said passageway, said conduit having holes therein for creating a water curtain across said passageway, which water will fall into said trap.

PETER GROVER BEVERIDGE.
